UNITED STATES PATENT OFFICE.

JOHN W. CHALLONER, OF OSHKOSH, WISCONSIN.

FRICITION-CLUTCH.

No. 831,215.

Specification of Letters Patent.

Patented Sept. 18, 1906.

Application filed July 31, 1905. Serial No. 272,090.

To all whom it may concern:

Be it known that I, JOHN W. CHALLONER, a citizen of the United States, residing at the city of Oshkosh, in the county of Winnebago and State of Wisconsin, have invented new and useful Improvements in Friction-Clutches, of which the following is a specification.

This invention relates to improvements in friction-clutches, and particularly to a friction-clutch adapted to the operation of a sawmill-carriage, shingle-machine carriage, and the like, or any device requiring reciprocal movement.

15 The object of the invention is the provision of means for facilitating the operation of a clutch requiring reciprocal movement.

With this and other objects in view the invention consists of certain other novel constructions, combinations, and arrangements of parts, as will be hereinafter fully described and claimed.

In the drawings, Figure 1 is a fragmentary perspective view of the frame of a machine and showing supported thereon a mechanism constructed in accordance with the present invention. Fig. 2 is a horizontal sectional view of the box above the shoe-operating device. Fig. 3 is a view in side elevation 25 with the side of the box removed. Fig. 4 is a perspective view of the box, shoe, and co-operating parts for actuating said shoe. Fig. 5 is a vertical longitudinal sectional view of the box of the shoe, showing the crank-arm 30 and a portion of the rocker-arm in side elevation. Fig. 6 is a perspective view of the shoe. Fig. 7 is a perspective view of the crank-arm.

Referring to the drawings, 2 designates a machine-frame, and 3 the carriage. The carriage 3 slides on usual ways or tracks 4 of the machine-frame 2. Power is applied to the pulley 5, which drives the pulley 6 upon the same shaft. An endless belt 7 is mounted upon and is driven by the pulley 6 beneath the roller 8 and around the idler-pulley 9. The tension of the belt is regulated by means of the bolt 10, set in the sliding pulley-frame 12 and passing through an eye in the lug 13. 45 The bolt 10 carries a nut 11. By adjusting the nut the tension of the belt is regulated.

A box 14 is fixedly secured to the carriage 3, and within said box a shoe 15 is positioned.

The box is open at both ends and the belt 7 passes through the box above and below said shoe 15, Figs. 1, 3, and 4. The shoe 15 is operated upwardly or downwardly against the belt 7 by means hereinafter described. The shoe when sufficiently so operated presses the belt either against the top or bottom of the box, thereby applying the friction to both the outer and inner surfaces of the belt. It will be understood that the top portion of the belt is always traveling oppositely to the bottom portion. Therefore reciprocation of the carriage is effected whenever the pressure of the shoe is changed.

The shoe 15 and the box 14 are preferably of the same shape, which is in the present instance rectangular. The shoe 15 is operated by the lever 16, pivoted to the carriage 3 at 17, and connected by means of a link 18 with a rocker-arm 19', which is fixedly secured to shaft 20. The shaft 20 is journaled in the sides of the box 14. An arm 21, constituting a crank, is fixedly mounted upon shaft 20, Fig. 5, and loosely incloses the shaft or pin 22, which shaft 20 is journaled in the sides of the shoe 15. The operation of the lever 16 rocks the shaft 20, and by 70 means of the crank 21 raises and lowers the shoe and confines the belt between the shoe 15 and the top or bottom of the box 14 sufficiently to apply the friction in any degree desired. This upward-and-downward movement, hereinbefore referred to, is therefore caused by automatically or manually swinging the rocker-arm 19', thereby rocking shaft 20. The belt 7 then carries the box 14, and the carriage 3 attached thereto, at a speed 75 corresponding to the friction applied. The lever 16 is operated longitudinally forward and backward, and the power-pulley 5 is revolved in the proper direction, so as to impart a forward movement to the carriage 3, 80 and likewise a backward pull upon the lever 16 will apply the friction to move the carriage 3 backward. When the pressure either way is removed from the lever 16, the spring 23, pressing against the upper end of the rocker-arm 19', will throw the shoe out of contact, thereby placing said rocker-arm, 85 preferably, in a vertical position.

The double-headed pin 24 passes loosely through an eye in the end of the rocker-arm 19', and said pin 24 upon each side of rocker-

arm 19' is surrounded by a coil-spring 24'. The arms 26, carried by the frame 2, serve as stops to stop and reverse the movement of the carriage. When the pin 24 strikes against the stop 26, one of the springs 24' is first compressed, forming a cushion until sufficient pressure is applied to operate the rocker-arm 19' and rock the shaft 20, causing the shoe 15 to press upon the belt for reversing the movement of the machine. An automatic safety-reverse is in this manner provided. Shoulder-bars 27 are carried by the ends of the shoe 15, Fig. 5, which bars constitute guiding means. These bars 27 travel up and down against the edges of box 14 to insure parallel movement of the shoe 15. In the drawings the said bars 27 are preferably attached by screws 28.

What I claim is—

1. In a friction-clutch, the combination with an endless belt, of a shoe interposed between the sides of said belt, a box entirely inclosing said shoe and belt, and means for bodily moving said shoe within said box against either surface of the belt.

2. In a friction-clutch, the combination with an endless belt, of a shoe interposed between the sides of said belt, a box entirely inclosing said shoe and belt, a shaft journaled within said box, a crank-arm fixed to said shaft and shoe, and means for rocking said shaft and thereby vertically moving said shoe.

3. In a friction-clutch, the combination with an endless belt, of a shoe interposed between the sides of said belt, a box inclosing said shoe and through which the belt passes, a shaft journaled within said box, a crank-arm fixed to said shaft, a pin extending through said crank-arm and positioned within said shoe, and means for rocking said shaft.

4. In a friction-clutch, the combination with an endless belt, of a shoe interposed between the sides of said belt, a box inclosing said shoe and through which box the belt passes, a rock-shaft journaled within the box, a crank-arm fixed to said shaft, a pin extending through said crank-arm and secured to said shoe, a rocker-bar fixed to said rock-shaft, a lever connected to the lower end of said rocker-bar, and stops arranged at proper distances to engage the upper end of said rocker-bar.

5. In a machine of the class described, the combination with a frame, tracks carried by said frame, a carriage engaging said tracks, of a box attached to said carriage, a shoe within said box, an endless belt passing through said box above and below said shoe, and means for pressing said shoe upwardly or downwardly against the surface of said belt.

6. In a machine of the class described, the combination with a frame, tracks carried by said frame, a carriage engaging said tracks, of a box attached to said carriage, a shoe po-

sitioned within said box, an endless belt passing through the box above and below said shoe, and means for vertically moving said shoe against the surface of said belt.

7. In a machine of the class described, the combination with a support, a traveling carriage carried by said support, of a box secured to said carriage, an endless, solid belt passing through said box, a shoe within said box and positioned between the sides of said belt, and means for pressing said shoe against said belt for reversing movement of said carriage.

8. In a machine of the class described, the combination with a frame, a carriage carried by said frame, of means for reversing movement of said carriage, stops carried by said frame and positioned in the path of movement of said reversing means, and means for controlling movement of said reversing means.

9. In a machine of the class described, the combination with a carriage, of a hollow box fixed to said carriage, a hollow shoe positioned within said box, an endless belt passing through said box and positioned between said shoe and box, and means for pressing said shoe against the inner surface of said belt for reversing movement of said carriage.

10. In a machine of the class described, the combination with a frame, of a traveling carriage carried by said frame, an endless belt carried by said frame, means fixed to said carriage and normally engaging said belt for reversing the movement of said carriage, and manually-operated means for controlling movement of said reversing means, comprising a substantially horizontal lever pivotally mounted upon said carriage, and a horizontal link pivotally connected to said lever and to said reversing means.

11. In a machine of the class described, the combination with a frame, of a traveling carriage carried by said frame, an endless belt carried by said frame, reversing means carried by said carriage and co-operating with said belt, and tensioning means for said belt, said tensioning means comprising a lug formed upon said frame, a pulley-frame provided with a threaded bolt, said bolt extending through said lug, a revoluble member carried by said bolt and normally engaging said lug, and a pulley journaled in said pulley-frame, said belt passing around said pulley.

12. In a machine of the class described, the combination with a traveling carriage, of a hollow box fixed thereto, an endless belt passing through said box, a vertically-movable, hollow shoe positioned within said box and adapted to press against the inner surface of the upper or lower portion of said belt, a rocker-bar carried by said box, a crank-arm positioned entirely within said hollow box, and means for rocking said crank-arm for causing said shoe to press against said belt.

13. In a machine of the class described, the combination with a frame, a traveling carriage carried by said frame, an endless belt carried by said frame, a box inclosing said 5 belt and fixed to said carriage, a shoe positioned within said box and adapted to press against said belt for reversing movement of said carriage, a rocker-bar connected to said shoe, a pin loosely mounted upon said rocker- 10 bar, cushioning means positioned upon said

pin, and stops carried by said frame and adapted to be engaged by said pin for pivoting said rocker-bar upon said box for moving said shoe.

In testimony whereof I affix my signature 15 in presence of two subscribing witnesses.

JOHN W. CHALLONER.
